UNITED STATES PATENT OFFICE.

LAURENCE J. BERKELEY, OF YOUNGSTOWN, OHIO.

SPIKE MACHINE.

Application filed September 8, 1922. Serial No. 587,008.

To all whom it may concern:

Be it known that I, LAURENCE J. BERKELEY, a citizen of the United States, residing at Youngstown, in the county of Mahoning 5 and State of Ohio, have invented new and useful Improvements in Spike Machines, of which the following is a specification.

This invention relates to machines for making spikes, bolts, and similar articles, and 10 more particularly to an automatic machine in which the stock is fed, cut, pointed, and headed by the automatic operation of the machine.

One object of my invention is to provide a 15 machine of the above character in which various operations are effected by mechanisms operated by fluid under pressure, so as to avoid the use of cams and cumbersome operating parts.

Another object of my invention is to provide a spike machine in which various operations are controlled electrically through the operation of a switch mechanism operatively associated with the machine.

Another object of my invention is to provide means for stabilizing the action of and thereby preventing any overrunning movement of the spike nipper carriage.

Another object of my invention is to provide a generally improved and simplified machine for the automatic production of spikes, bolts, and the like.

Other objects and advantages will appear in the following more detailed description 35 of the invention.

In the accompanying drawings; Fig. 1 is a side elevation of a spike making machine embodying my invention; Fig. 2 a plan view of the machine, omitting certain parts 40 and showing more particularly the nipper mechanism; Fig. 3 a central vertical section of the construction shown in Fig. 2; Fig. 4 a section on the line 4—4 of Fig. 3; Fig. 5 a plan view of the machine, omitting certain 45 parts and showing more particularly the spike heading mechanism; Fig. 6 a partial section on the line 6—6 of Fig. 5; Fig. 7 a front elevation of the toggle lever and gripe mechanism; Fig. 8 a section on the line 8—8 50 of Fig. 7; Fig. 9 a section on the line 9—9 of Fig. 7; Fig. 10 a central vertical section of the "stabilizer" mechanism; Fig. 11 a vertical section of the nipper operating cylinders; Fig. 12 a detail face elevation of the 55 adjustable crank arm of the nipper mecha-

nism; Fig. 13 a side elevation of the adjustable crank arm; Fig. 14 a section on the line 14—14 of Fig. 12; Fig. 15 a vertical sectional view of a portion of the spike machine, showing more particularly the gripe mechanism and the blank holding die clamping 60 means; Fig. 16 a detail plan view, showing the lateral die for clamping the spike blank laterally; Fig. 17 a side elevation of the parts shown in Fig. 16; Fig. 18 a detail view 65 showing means for clamping the blank holding die in place; Fig. 19 a view showing the so-called "hand machine" spike head; Fig. 20 a view showing the so-called "automatic machine" spike head; Fig. 21 a detail side 70 view, partly in section, of the mechanism for guiding the spike blank; Fig. 22 an end elevation of the parts shown in Fig. 21; Fig. 23 a face view of the electric switch contact 75 controlling device, including a diagram illustrating the various circuits controlled thereby; Fig. 24 a vertical section of the switch device shown in Fig. 23; Fig. 25 a diagram showing the relation of the switch drum contacts; and Fig. 26 a diagrammatic 80 view of one of the magnet controlled valve devices.

The machine may comprise a main frame 1 having housings 2 at one end in which are mounted bearings for parallel horizontal 85 shafts 3 carrying feed rolls 4 for feeding the stock from which the spike blanks are cut. The feed rolls are provided with knives 5 adapted to point the spike blank and also substantially sever the blank from the stock 90 bar. Secured to the shafts 3 are meshing gears 6 by which the feed rolls are rotated in unison.

Secured to the opposite end of the lower feed roll shaft 3 is a gear 7 which meshes 95 with a gear 8 secured to a shaft 9. The opposite end of the shaft 9 carries a ratchet wheel 10 which is engaged by a pawl 11 mounted on a rocker arm 12, as shown more particularly in Fig. 6, so that when the arm 100 12 is rocked, the pawl 11 partially rotates the ratchet wheel 10 and thus causes an intermittent rotative movement of the feed rolls 4.

At an intermediate point a horizontal 105 main shaft 13 is laterally mounted in suitable bearings in the frame 1 and secured to the opposite ends of the main shaft are eccentrics 14 for operating corresponding connecting rods 15. Each connecting rod is piv- 110

totally connected to a rocker arm 16 and one of the rocker arms is provided with an arm 17 which is operatively connected to the rocker arm 12 by means of a connecting rod 18 having a right and left hand nut 19 by which the length of the rod may be adjusted.

Mounted in suitable guides in the frame to reciprocate horizontally is a nipper carriage 20 (see Figs. 2 and 3) and operatively connected to said carriage is a connecting rod 23, one end of which is pivotally connected to a lever arm 21 carried by a shaft 22 having bearings in the main frame 1. Secured to one end of the shaft 22 is an adjustable crank arm (hereinafter described more in detail) the yoke portion 118 of which is pivotally connected to a connecting rod 24. The other end of the connecting rod 24 is pivotally connected to an arm 25 which is carried by the rocker arm 16 opposite to that rocker arm 16 carrying the arm 17. The connection of the rod 23 to the nipper carriage is through a pin 26 mounted in bearings in lugs 27 carried by the nipper carriage. On the pin is mounted a block 28 which is adapted to operate in a slot in the end of the connecting rod, so that there will be a certain amount of lost motion "a" in the operation of the carriage in order to provide a pause in the movement of the carriage at opposite ends of its travel for purposes to be hereinafter described.

Pivots mounted on pins 29 secured to the nipper carriage are nippers 30 by which the blank is carried forward from the feed rolls to the heading position. The nippers have nipper jaws 31 keyed to one end of the nippers and pivotally connected to the other end of each nipper is a piston 32 mounted in a common cylinder 33 which is carried by the nipper carriage 20. In order to compel equal and uniform movement of both nippers, each piston carries a rack bar 34, both rack bars meshing with a common pinion 35, so that movement of one piston compels a corresponding movement of the other piston.

The gripping movement of the nippers 30 is effected by supplying fluid under pressure through a port 36 to a chamber intermediate the pistons 32 and the release movement is effected by means of leaf springs 37, each secured to a lug 38 associated with each hub 39 of the nipper carriage on which each nipper 30 is mounted, as shown in Fig. 3. The free end of each spring may be flexed by means of a cam member 39 mounted on and carried by each nipper 30. When it is desired to open the nippers so as to change dies, the cam members 39 may be rotated by applying a wrench to the squared portion 39^a, so as to throw the cam out of engagement with the spring, thus relieving the nippers of the pressure of the springs.

The spike heading mechanism may comprise, as shown more particularly in Figs. 5 and 6, a slide frame 40 which is pivotally supported at one end on pins 41 secured in the gripe and toggle housing 42. The opposite end of the frame 40 is supported by two elevator rods 43 having screw threaded connection with a double nut member 44 which has trunnion bearings in the slide frame 40. The rods 43 are mounted in a yoke 45 and are provided with bevel gears 46 adapted to mesh with bevel gears 47 secured to a transverse operating shaft 48, which shaft also serves as a bearing support for the yoke 45, the shaft being mounted in bearings in the main frame 1. The end of the shaft 48 is squared as at 49 for receiving a handle or ratchet wrench by which the shaft 48 may be rotated and thereby the rods 43 through the bevel gear connections, so as to raise or lower the slide frame 40.

Slidably mounted in the slide frame 40 is a header carriage 50 which is operatively connected to the rocker arm 16 by means of connecting rods 51. Within the carriage 50 is mounted a header die 52 for heading the spike, the die being adjustably held in position by means of set screws 53 and 54.

The header die 52 is positioned to engage the end of the spike blank after the blank 55 has been deposited in the receiving channel of the die block 56.

The spike blank is held in position for heading by means of a gripe and toggle mechanism comprising, as shown more particularly in Figs. 7 and 8, a vertically arranged housing 42 mounted on the main frame 1 and having slidably mounted therein a gripe die ram 57. The ram 57 is secured to a guide rod 58 which is guided in a bearing 59 in the housing and is connected to a member 60 having slide bearings in the housing. Pivots connected to the member 60 is a toggle arm 61 and pivotally connected to the arm 61 is the other toggle arm 62. The toggle arm 61 is provided with a lug 63 adapted to engage a portion of the arm 62 when the toggle arms are moved to the closed position, which may be either on or slightly beyond the vertical alining position of the arms, so that when pressure is applied to the toggle mechanism the engagement of the lug with the toggle arm 62 will hold the parts in position and prevent the arms from doubling up. The lug 63 may also be provided with laterally projecting portions 171 adapted to engage corresponding lugs 172 carried by the member 62 when the toggle joint has been moved to the desired open position, so as to limit the operating movement of the toggle joint.

The toggle arm 62 is pivotally connected to a member 64 having slide bearings in the housing 42 and the member 64 is secured to a piston rod 65 working in a bearing 66 in

the housing 42, the piston rod 65 being connected to a piston 89 mounted in a cylinder 67 which is secured to the housing 42. The piston 89 is subject on one side to the pressure of a coil spring 90 and is operated by fluid under pressure supplied to the opposite side through a port 68. The admission and release of fluid under pressure to and from piston 66 is controlled by a magnet valve device 69.

The opening and closing of the toggle mechanism is controlled by a double acting piston 70 contained in a cylinder 71 pivotally mounted on the housing 42. The piston 70 is provided with a stem 72, which is pivotally connected to an arm 73 carried by the toggle arm 62 and said stem is provided with suitable packing rings 74 to prevent leakage of fluid pressure past the stem. The opposite side of the piston 70 is also provided with a stem 75 having packing rings 76 to prevent leakage from the piston chamber 80 at the corresponding side of the piston. A magnet valve device 77 controls the admission and release of fluid under pressure to the piston chamber 78 at one side of the piston 70 for operating the piston to effect the opening of the toggle joint and a magnet valve device 79 controls the admission and release of fluid under pressure to the piston chamber 80 at the opposite side of the piston for operating the piston to effect the closing of the toggle joint.

Secured in the ram 57 is a grieve member 81 which is adapted to vertically engage the spike blank and hold the same while the blank is being headed.

The channel in the receiving die block of the usual automatic spike machine is made with tapered sides to facilitate the dropping of the spike blank into the die channel by the nippers and consequently the blank is held only by the vertically acting grieve while the blank is being headed. This lateral tapered clearance in the die block causes the production of a heavy and sometimes undesirable fillet under the head of the spike, as the material of the blank is upset in heading operation, such a head being known as the "automatic head", and as shown in Fig. 20. In hand spike making machines, box dies may be used which close all around the blank so that the head of the spike may be formed without the undesirable fillet above referred to, as shown in Fig. 19. With my machine a "hand machine head" may be made when desired and this is accomplished by providing a lateral gripping die in addition to the vertical grieve.

For this purpose, the die 56^a is cut away at one side at the header end as shown in Fig. 16 and the channel 55 at opposite side is shaped to conform to the contour of the spike blank and the desired shape of the inner portion of the head, the rear portion of

the channel 55 being left tapered as in the ordinary die to permit the blanks to be dropped into the channel by the nippers.

A side die 82 operates in the space provided by cutting out the die 56^a and said die is shaped to conform to the contour of the spike blank and the desired shape of the inner portion of the head. The die 82 is operated by a lever 83^a supported by a fulcrum pin 84 and having its lower end operatively connected to a piston rod 85. The piston rod 85 is connected to a piston 86 operating in a cylinder 87 secured to the housing 42 as shown in Fig. 15. The cylinder 87 is connected by a port 88 to a pipe 149 through which fluid under pressure may be supplied to the cylinder and preferably at the same time that fluid is supplied to the grieve cylinder 67, so that the side die operates to grieve the blank simultaneously with the operation of the vertical grieve 81, thus holding the blank on all four sides.

When the usual solid die 56 is employed and the side die clamping feature is dispensed with, the lever 83 may be employed to clamp the die 56 in place. In this case, a hand operated three way cock 148 is placed in the pipe 149 which is then connected to a source of fluid pressure supply.

When the die 56 has been positioned in the machine, the cock 148 is turned to its position for admitting fluid under pressure to the piston 86 and the piston then acts on the lever 83 to clamp the die 56 in position. Fluid pressure is maintained on the piston 86 while the machine is running, but if it is desired to change dies, the cock 148 is turned to a position for venting fluid from the piston 86, so that the lever 83 will be released from its clamping position, permitting the die 56 to be removed.

If the lateral die 82 is employed, the die 56^a may be maintained in position by means of a clamping bolt 150, the head of which is adapted to engage in a T slot in the die 56^a and which extends through the die holder 151 as shown in Fig. 18.

The lost motion *a* which permits a relative movement of the connecting rod 33 with respect to the nipper carriage 20 for a purpose to be hereinafter described may cause an overrunning of the carriage due to momentum, and if not restrained, would tend to prevent the correct positioning of the nippers in the act of gripping the spike blank and in the act of dropping the blank into the receiving die.

In order to prevent this, I provide means for resisting the movement of the carriage which has its maximum effectiveness at the end of the travel of the carriage where the direction of motion of the connecting rod 33 is reversed. I have termed this means a "stabilizer" and as shown more particularly in Fig. 10 of the drawings, the stabilizer

- may comprise a cylinder 91 secured to the main frame 1 and containing a piston 92 operatively connected by a piston rod 93 with the nipper carriage 20. The piston chamber 94 at one side of piston 92 is provided with an inlet port 95 through which a liquid, such as water, is supplied to the piston from a supply pipe 96 past a non-return check valve 97.
- 10 The piston chamber 98 is provided with a similar inlet port 99 through which liquid is supplied from the pipe 96 past a check valve 100.
- An exhaust valve 101 controls the outflow of liquid from piston chamber 94 through port 102 and an exhaust valve 103 controls the outflow of liquid from piston chamber 98 through port 104. The valve 101 is subject to the pressure of a coil spring 105, the compression of which may be varied by the movement of a stem rod 106 and the valve 103 is subject to the pressure of a spring 107, the compression of which may be varied by the movement of a stem 108.
- 20 A bell crank 109 has the end of one arm engaging the end of stem 106 with the other arm pivotally connected to a link 110 and a bell crank 111 has the end of one arm engaging the end of stem 108 with the other arm also connected to link 110.
- The link 110 is pivotally connected to a link 112 which is pivotally connected to one end of a fulcrumed lever 113, the other end of the lever 113 being connected, through a link 114 to a member 115 which is secured to a stem 116 carried by the piston 92.
- 30 In the operation of the above described stabilizing device, liquid under pressure being supplied from a suitable source to pipe 96, flows past the check valves 97 and 100 to the respective piston chambers 94 and 98. When the nipper carriage 20 moves to the left, the liquid in piston chamber 94 is forced out through passage 102 and past the check valve 101 to an exhaust chamber 117, and thereby offers a resistance to the movement of the piston 92 and the nipper carriage 20. Initially this resistance is very slight, but as the carriage 20 moves to the left, the stem 116 operates the lever 113 so as to rock the arm 109 in a direction to compress the spring 105 through the movement of the stem 106. It will thus be seen that the flow of liquid from piston chamber 94 is increasingly opposed as the nipper carriage approaches the end of its travel to the left and consequently any tendency of the nipper carriage to overrun, due to the lost motion α is prevented and the carriage 20 is firmly maintained in its desired operating position. At the end of the travel to the left, after the lost motion α has been taken up in the reverse movement to the right, the movement of the stem 116 operates the lever 113 to cause the arm 109 to compress the spring 107 at the same time moving the arm 109 to relieve the compression of spring 105. The resistance to the outflow of liquid from piston chamber 98 past the check valve 103 is thus gradually increased until at the end of the travel to the right, the maximum resistance is attained. By means of the above construction, the nipper carriage is prevented from moving independently of the operating connection as might be occasioned either by momentum or otherwise.
- 40 In order to regulate the traverse of the nipper carriage, as may be required for different length spikes or bolts, an adjustable crank arm is interposed in the operating mechanism, as shown in detail in Figs. 12, 13, and 14, and said crank arm may comprise a yoke 118 and a crosshead 119 slidably mounted in said yoke and having a bearing on the shaft 22. The yoke 118 is provided with a lug 120 having a threaded opening for receiving an adjusting screw 121. The screw 121 extends through an opening in the shaft 22 and is provided with collars 122 adapted to engage flat faces provided on opposite sides of the shaft. The end of the screw 121 is provided with a hand wheel 123 and when it is desired to adjust the throw of the yoke 118 and thereby the travel of the nipper carriage, the hand wheel 123 is operated to turn the screw 121, in one direction for lengthening the crank arm, and in the opposite direction for shortening the crank arm. With the crank arm shortened, the movement of the yoke 118 by the connecting rod 24 will cause an increased travel of the nipper carriage 20 and by lengthening the crank arm, the travel of the carriage is reduced, as will be evident.
- 50 In order to adjust the position of the nipper carriage with respect to the spike blank at the end of its travel, a right and left hand adjusting nut 124 may be interposed in the connecting rod 24.
- 60 A magnet controlled valve mechanism is preferably employed for controlling the admission and release of fluid under pressure to each of the various operating cylinders of the machine and since the same magnet controlled valve mechanism may be employed in each instance, a description of one will apply to all.
- 70 The magnet controlled valve mechanism may comprise, as shown diagrammatically in Fig. 26, a magnet 125 for operating a double beat pilot valve 126 and a relay valve construction comprising a piston 127 contained in a casing 128, an exhaust valve 129, and a supply valve 130 adapted to be operated by piston 127.
- 80 When magnet 125 is deenergized, the double beat pilot valve 126 is in a position in which fluid is vented from piston 127, per-

mitting spring 131 to hold the valve 130 closed and the exhaust valve 129 open, so that pipe 132 which is connected to the corresponding operating cylinder is vented to the atmosphere. When the magnet 125 is energized, the double beat pilot valve is moved to a position in which fluid under pressure is supplied from a fluid pressure supply pipe 133 to piston 127 so that the piston is operated by fluid under pressure to close the exhaust valve 129 and open the supply valve 130. Fluid under pressure is then supplied to the corresponding operating cylinder.

15 In order to control the energization and deenergization of the controlling magnets and to effect the desired sequence and timing of the operations of the machine, a contact switch mechanism is provided which may 20 comprise, as shown in Figs. 23 and 24, a contact drum 134 secured to one end of the main shaft 13. On the drum 134 are mounted disks 135 of insulating material, each carrying a contact segment as follows, a supply 25 ring 136, toggle open contact segment 137, toggle close segment 138, gripe segment 139 and nipper segment 140, each of the segments being electrically connected to the supply ring contact 136.

30 Mounted on the shaft 13 adjacent to the contact drum is a disk 141 which may be held against rotation by means of a stud 142 secured to the main frame 1 of the machine. Pivotally mounted on the disk 141 are a 35 plurality of contact carriers 143, each provided with a contact roller 144 adapted to engage a corresponding contact segment on the drum.

Secured at the pivot pin 145 of each contact carrier 143 is a flat spring 146 which engages a projecting finger 147 carried by each carrier, so as to press the contact roller into engagement with the corresponding contact segment.

45 As indicated in the diagram shown in Fig. 25, the nipper contact segment engages the nipper contact roller through 180° of each revolution of the main shaft, the toggle open contact through 295°, the toggle close contact through 65°, and the gripe contact segment through 45°, the contacts being spaced as indicated in the diagram to give the proper and desired timing.

55 Due to possible inaccurate setting of the feed rolls or the blank cutting knives, the blank as fed from the rolls may not maintain the desired horizontal position, so that the blank may not be in position to be grasped by the nippers. In order to avoid this, a guiding mechanism is provided, as shown in detail in Figs. 21 and 22, comprising a finger 152 which is secured to a shaft 153 transversely mounted in the main frame 1. The finger 152 is positioned so as to engage the upper side of the spike blank as

it is fed from the feed rolls and hold the same down in horizontal alignment until the nippers are advanced to grasp the blank. In order to throw the finger 152 out of the way so as not to interfere with the grasping movement of the nipper jaws, a cylinder 154 is provided, which contains a piston 155 having a stem 156. The stem 156 is pivotally connected to arm 157 secured to the shaft 153, so that when fluid under pressure is supplied to piston 155, the piston operates through the arm 157 to rotate the shaft 153 and thereby shift the finger 152 upwardly and out of the way of the nipper jaws. The spring 166 acting on piston 155 normally maintains the guide finger 152 in position for engaging the spike blank.

A magnet controlled valve mechanism 158 controls the admission and release of fluid under pressure through pipe 159 to and from piston 155 and preferably the magnet of the valve mechanism is connected in the circuit of the magnet which controls the nippers. Although fluid under pressure will thus be supplied to the guide controlling cylinder at the same time that fluid is supplied to the nipper controlling cylinder, the port areas are such that the piston 155 of the guide controlling mechanism will operate to lift the guide finger before the nippers move to grip the spike blank.

After the spike blank has been headed, the blank must be removed and for this purpose a stripping mechanism is provided comprising an ejector bar 160, one end of which extends into an opening in the die 56 and the other end of which engages one arm of a bell crank 161 which is mounted in bearings in the main frame 1, as shown in Fig. 1. The other arm of the bell crank 161 is pivotally connected to a link 162, the other end of which is pivotally connected to one arm of a bell crank 163. The other arm of the bell crank 163 is provided with a cam roller 164 adapted to engage a cam 165 which is mounted on the main shaft 13. The cam is so constructed and positioned that at the desired time in the rotation of the main shaft, the bell crank mechanism is actuated so as to operate the ejector bar 160 and cause the spike blank to be thrown out of the holding die.

Having described the construction of the machine and to some extent the operation of certain parts, the operation of the machine as a whole will now be described.

The stock from which the spikes or bolts are to be made is supplied to the feed rolls 4 and the rotation of the main shaft 13 causes the partial rotation of the ratchet wheel 10 by the action of the pawl 11, the eccentrics 14 operating the arms 16 through the connecting rods 15 and thereby the arm 17 and the pawl carrying member 12 through the connecting rod 18. As the feed rolls rotate,

a cooperating pair of knives 5 engage the stock and by their action form the points on the spike blank and nearly sever the blank from the stock. The spike blank passes 5 under the guide finger 152 which ensures that the blank will be guided in position so that it may be gripped by the nippers.

While the spike blank is being fed out, the nipper carriage 20 is moving forward 10 through the movement of the crank arm 25, connecting rod 24, yoke 118, arm 21, and the connecting rod 23. At the end of the forward travel of the nipper carriage 20 and during the pause in the reverse movement 15 of the carriage occasioned by the lost motion α at the end of the connecting rod 23, the drum of electric switch contact mechanism has rotated so as to bring the nipper contact segment 140 into engagement 20 with the corresponding nipper contact roller 144. The magnet of the nipper magnet controlled valve mechanism 180 is then energized, so that the double beat pilot valve 126 is operated to supply fluid under pressure 25 to the relay piston 127. The relay inlet valve 130 is then opened to supply fluid under pressure to the nipper operating pistons 32. The outward movement of the pistons 32 causes the nippers 30 to close in the 30 nipper jaws 31 so that the spike blank X is gripped. At the same time, the magnet of the valve mechanism 158 which controls the fluid pressure on the guide piston 155 is energized, being in circuit with the nipper 35 magnet, so that fluid under pressure is supplied to the guide piston 155.

The piston 155 moves more quickly than the nipper pistons 32, as hereinbefore described, so that the guide finger 152 is 40 thrown out of the way before the nipper jaws engage the spike blank.

The spike blank is now carried rearwardly until the blank is positioned above the receiving channel 55 in the die 56. At this 45 position, the nipper carriage is at the end of its rearward travel. There is now a pause in the movement of the nipper carriage due to the lost motion α before the reverse movement of the carriage takes place and during this pause the electric switch contact drum has rotated so that the circuit of the 50 nipper magnet is opened and fluid under pressure is thus released from the nipper pistons 32. The nipper springs 37 then 55 operate the nippers 30 so that the nipper jaws 31 open up and permit the spike blank to drop into the receiving channel of the die 56.

As the nipper magnet is deenergized, the 60 magnet of the toggle close magnet controlled valve mechanism 79 is energized by the action of the rotating switch drum, so that fluid under pressure is supplied to piston chamber 80 (see Fig. 8) of the toggle controlling piston 70. The operation of the 65

piston 70 then closes the toggle joint and then the magnet of the magnet controlled valve mechanism 69 is energized, so that fluid under pressure is supplied to the gripe piston 89. By reason of the preliminary movement effected by the toggle joint action, only a slight movement of the gripe piston 89 is required to cause the gripe 81 to engage and firmly clamp the spike blank in its position in the receiving channel of the 70 die 56.

If "hand machine" heads are being made, the lateral clamping die 82 is employed and the piston 86 being then connected to receive fluid under pressure at the same time that fluid is supplied to the gripe piston 89, the die 82 is operated by the lever 83^a to gripe the spike blank laterally at the same time that the blank is gripped by the operation of the gripe 81.

The header carriage 50, being connected to the rocker arms 16 through the connection rods 51, moves forward as the nipper carriage 20 moves rearwardly and the parts are so related that the header carriage 50 moves the header 52 so as to head the spike just after the spike blank has been gripped in the heading position by the gripe 81. The heading of the spike takes place at the end 90 of the travel of the header carriage 50, as shown in Fig. 6, and then the header carriage starts on its rearward travel.

After the heading operation, the contact switch mechanism operates to open the circuits of the toggle close magnet and the gripe magnet and at the same time cause the closing of the circuit of the magnet of the magnet controlled valve mechanism 77. Fluid under pressure is then supplied to the 100 piston chamber 78 and the piston 70 operates through the arm 73 to open the toggle joint.

When the gripe 81 moves upwardly, the spike blank is discharged by the operation of the ejector rod 160 and the blank drops to an apron 170, whence it is deposited in the usual receptacle provided therefor.

The nipper carriage is now moving forward while another spike blank is being fed out by the operation of the feed rolls and the continued operation of the machine in the manner above described takes place.

As hereinbefore described, the "stabilizer" operates to stabilize the movement of the nipper carriage 20, so that said carriage will not move of itself or overrun independently of the moving force, as would otherwise be possible on account of the lost motion α , and consequently the carriage will not assume a position other than the desired position, as determined by the operation of the connecting rod 23.

Having now described my invention, what I claim as new and desire to secure by Letters Patent, is:—

1. In a spike machine, the combination

with a reciprocating carriage and a pair of nippers pivotally mounted on said carriage, of a cylinder mounted on said carriage, opposing pistons in said cylinder operatively connected to said levers, and means for supplying fluid under pressure to the chamber intermediate said pistons.

2. In a spike machine, the combination with a reciprocating carriage and nippers mounted on said carriage for conveying the spike blank, of a cylinder mounted on said carriage, pistons in said cylinder for operating said nippers, and means operated upon forward movement of said carriage for supplying fluid under pressure to said pistons and upon rearward movement of said carriage for releasing fluid from said pistons.

3. In a spike machine, the combination with a reciprocating carriage and nippers carried by said carriage for conveying the spike blank, of fluid pressure controlled means for operating said nippers, a valve for controlling the fluid pressure for operating said means, and electrically controlled means for operating said valve.

4. In a forging machine, the combination with a reciprocating carriage and clamping members carried by said carriage, of fluid pressure controlled means for operating said members and means operated upon the forward movement of said carriage for supplying fluid under pressure to said fluid pressure controlled means and upon rearward movement of said carriage for releasing fluid from said fluid pressure controlled means.

5. In a spike machine, the combination with a reciprocating carriage and nippers carried by said carriage, of electro-fluid-pressure means for controlling the opening and closing of said nippers and an electric contact device operatively associated with the spike machine for controlling the electric circuit of said electro-fluid-pressure means.

6. In a spike machine, the combination with a mechanically operated reciprocating carriage and nippers carried by said carriage for gripping the spike blank, of fluid pressure controlled means for opening and closing said nippers, a magnet controlled valve for controlling the fluid pressure on said means, and an electric switch mechanism operatively associated with the spike machine for opening and closing the circuit of said magnet.

7. In a spike machine, the combination with a spike blank gripping mechanism and a fluid pressure operated movable abutment for operating said gripping mechanism, of a toggle joint interposed between said gripping mechanism and said movable abutment, and fluid pressure operated means for opening and closing said toggle joint.

8. In a spike machine, the combination

with a spike blank gripping mechanism and a fluid pressure operated movable abutment for operating said gripping mechanism, of electrically controlled means for controlling the fluid pressure on said abutment.

70

9. In a spike machine, the combination with a spike blank gripping mechanism and a fluid pressure operated movable abutment for operating said gripping mechanism, of electrically controlled means for controlling the fluid pressure on said abutment, and an electric switch device operatively associated with the spike machine for controlling the circuit of said electrically controlled means.

75

10. In a spike machine, the combination with a spike blank gripping mechanism and a fluid pressure operated movable abutment for operating said gripping mechanism, of a toggle joint interposed between said gripping mechanism and said movable abutment, fluid pressure operated means for opening and closing said toggle joint, and means operatively associated with the spike machine for controlling the fluid pressure on said movable abutment and on said fluid pressure operated means.

80

11. In a spike machine, the combination with a spike blank gripping mechanism and a fluid pressure operated movable abutment for operating said gripping mechanism, of a toggle joint interposed between said gripping mechanism and said movable abutment, fluid pressure operated means for opening and closing said toggle joint, electrically controlled means for controlling the fluid pressure on said movable abutment and on said fluid pressure operated means, and an electric switch contact mechanism operatively associated with the spike machine for controlling the electric circuits of said electrically controlled means.

85

12. In a spike machine, the combination with a spike blank gripping mechanism and a fluid pressure operated movable abutment for operating said gripping mechanism, of a quick take-up mechanism interposed between said gripping mechanism and said abutment for also operating said gripping mechanism, means for first operating said take-up mechanism, and means for then supplying fluid under pressure to said abutment.

90

13. In a spike machine, the combination with a vertically movable member for engaging the spike blank and a fluid pressure operated movable abutment for pressing said member into engagement with the spike blank, of a laterally movable die for engaging the spike blank, a vertically disposed lever having one end operatively connected to said die, a fluid pressure operated movable abutment operatively connected to the other end of said lever, and means for supplying fluid under pressure to said movable abutments.

14. In a spike machine, the combination with a vertically movable member for engaging the spike blank and a fluid pressure operated movable abutment for pressing said member into engagement with the spike blank, of a laterally movable die for engaging the spike blank, a vertically disposed lever having one end operatively connected to said die, a fluid pressure operated movable abutment operatively connected to the other end of said lever, and means for simultaneously supplying fluid under pressure to said movable abutments.

15. In a spike machine, the combination with a reciprocating carriage, spike blank nippers carried by said carriage, and a gripe mechanism for clamping the spike blank, of fluid pressure controlled means for opening and closing said nippers and for operating said gripe mechanism and electrically controlled means for controlling the fluid pressure on said fluid pressure controlled means.

16. In a spike machine, the combination with a reciprocating carriage, spike blank nippers carried by said carriage, and a gripe mechanism for clamping the spike blank, of fluid pressure controlled means for opening and closing said nippers and for operating said gripe mechanism, electrically controlled means for controlling the fluid pressure on said fluid pressure controlled means, and an electric switch contact device operatively associated with the spike machine for controlling the electric circuits of said electrically controlled means.

17. In a spike machine, the combination with a nipper mechanism for clamping the spike blank and carrying the same rearwardly, means for heading the spike blank in the rearward position, and a gripe mechanism for clamping the spike blank in the heading position, fluid pressure controlled means for operating said nipper mechanism to clamp the spike blank, fluid pressure controlled means for operating said gripe mechanism, valves for controlling the fluid pressure to said fluid pressure controlled means, magnets for operating said valves, and an electric switch contact device operating in timed relation with the operation of the spike machine for controlling the circuits of said magnets.

18. In a spike machine, the combination with feed rolls for feeding the spike blank, of a member for guiding the spike blank as it leaves the feed rolls, a spring normally pressing said member into engagement with the spike blank, and fluid pressure controlled means for shifting said member out of engagement with the spike blank.

19. In a spike machine, the combination with feed rolls for feeding the spike blank, of a member for guiding the spike blank as

it leaves the feed rolls, nippers for engaging the spike blank to carry the blank rearwardly, and fluid pressure controlled means for shifting said member out of its guiding position to permit the nippers to engage the blank.

20. In a spike machine, the combination with feed rolls for feeding the spike blank, of a member for guiding the spike blank as it leaves the feed rolls, nippers for engaging the spike blank to carry the blank rearwardly, fluid pressure controlled means for operating said nippers, fluid pressure controlled means for operating said member to shift same out of its guiding position, and electrically controlled means on the same electric circuit for controlling the fluid pressure on both fluid pressure controlled means.

21. In a spike machine, the combination with feed rolls for feeding the spike blank, of a member for guiding the spike blank as it leaves the feed rolls, fluid pressure controlled means for shifting said member out of its guiding position, electrically controlled means for controlling the fluid pressure on said fluid pressure controlled means, and an electric switch contact mechanism operatively associated with the spike machine for controlling the electric circuit of said electrically controlled means.

22. In a spike machine, the combination with a main frame, of a member pivotally mounted at one end on said frame, a carriage slidably mounted on said member, a header tool carried by said carriage for heading the spike blank, a screw-threaded rod for supporting the other end of said member, and means for operating said rod to raise and lower the corresponding end of said member.

23. In a spike machine, the combination with a reciprocating carriage, of an operating member for said carriage having a lost motion connection to the carriage and means for imposing a liquid under pressure resistance to the movement of the carriage.

24. In a spike machine, the combination with a reciprocating carriage, of an operating member for said carriage having a lost motion connection to the carriage, means for imposing a liquid pressure resistance to the movement of the carriage and means for increasing the liquid pressure resistance during the stroke of the carriage.

25. In a spike machine, the combination with a reciprocating carriage, of an operating member for said carriage having a lost motion connection to the carriage, means for imposing a liquid pressure resistance to the movement of the carriage and means for increasing the liquid pressure resistance as the carriage approaches the end of its stroke.

26. In a spike machine, the combination with a reciprocating carriage and nippers

- carried by said carriage for conveying the spike blank, of a member for operating said carriage having a lost motion connection to the carriage and a piston subject to liquid 5 under pressure and connected to said carriage for opposing movement of the carriage.
27. In a spike machine, the combination with a reciprocating carriage, of a piston 10 subject to liquid under pressure and connected to said carriage for opposing movement of the carriage, a valve for permitting the escape of liquid from said piston, and means operated by the movement of the piston 15 for increasing the load on the valve.
28. In a spike machine, the combination with a reciprocating carriage, of a piston subject to liquid under pressure and connected to said carriage for opposing movement 20 of the carriage, a valve for permitting the escape of liquid from said piston, a spring acting on said valve, and means operated by the movement of said piston for compressing the spring.
29. In a spike machine, the combination 25 with a reciprocating carriage, of a piston subject to liquid under pressure and connected to said carriage for opposing movement of the carriage, a valve for permitting the escape of liquid from said piston, a
- spring acting on said valve, and means operated by the movement of the piston in one direction for compressing the spring and by movement of the piston in the opposite direction for relieving the compression of 35 the spring.
30. In a spike machine, the combination with a reciprocating carriage, of a piston connected to said carriage and subject on opposite sides to liquid under pressure, a 40 valve for permitting the flow of liquid from each side of the piston, and means for increasing the load on one valve as the piston moves in one direction and for increasing the load on the other valve as the piston 45 moves in the opposite direction.
31. In a spike machine, the combination with a reciprocating carriage, of a piston connected to said carriage and subject on opposite sides to liquid under pressure, a 50 valve for permitting the flow of liquid from each side of the piston, a spring for opposing the opening of each valve, and means operated by the movement of the piston in one direction for compressing one spring and 55 upon movement of the piston in the opposite direction for compressing the other spring.

In testimony whereof I have hereunto set my hand.

LAURENCE J. BERKELEY.
